UNITED STATES PATENT OFFICE.

FRED ASHWORTH, OF BEVERLY, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

SEWING MACHINE.

Application filed September 22, 1915, Serial No. 52,006. Renewed January 15, 1920. Serial No. 351,562.

To all whom it may concern:

Be it known that I, FRED ASHWORTH, a citizen of the United States, residing at Beverly, in the county of Essex and State 5 of Massachusetts, have invented certain new and useful Improvements in Sewing Machines; and I do hereby declare the following to be a full, clear, and exact description of the invention, such as will enable others 10 skilled in the art to which it appertains to make and use the same.

The present invention relates to wax thread shoe sewing machines, and more particularly to mechanism employed in connection with such machines for grooving 15 the sole of a boot or shoe.

In the type of machine in which the present invention is embodied the presser foot is maintained in engagement with the work during the formation of a stitch and is entirely removed from engagement with the work during the feeding movement. 20

An object of the present invention is to provide certain new and useful improvements in a machine of this type which will adapt the machine for forming a groove in the outsole during the outsole stitching operation. With this object in view a feature 25 of the invention consists in the combination with a presser foot and grooving knife supported thereby, of mechanism for actuating the presser foot under the control of the operator to cause the removal of the presser foot from the work during the feeding movement, or to retain the presser foot 30 in yielding engagement with the work during the feeding movement. According to this feature of the invention the machine may be operated in the usual manner to clamp the work during the formation of a stitch and to entirely remove the presser foot from the work during the feeding movement when no groove is to be formed in the outsole, or the presser foot 35 mechanism may operate to relieve the positive pressure of the foot upon the work without entirely removing the presser foot from the work when forming a groove in the outsole.

50 In the accompanying drawings illustrating the preferred form of the invention; Figure 1 represents a side elevation of a

sewing machine embodying the invention; Figs. 2 and 3 are details representing the presser foot actuating mechanism in position respectively to maintain the presser foot in engagement with the work during the feeding movement and to entirely remove the presser foot from the work during the feeding movement; Figs. 4 and 5 are 55 details showing side elevations of the mechanism illustrated in Figs. 2 and 3; Fig. 6 is a view showing a cross section upon the line 6—6 of Fig. 4; Fig. 7 is a detail showing a cross section upon the line 7—7 of Fig. 2; and Fig. 8 is a detail illustrating the 60 method of supporting the grooving knife upon the presser foot.

The machine shown in the illustrated embodiment of the invention is substantially 70 the same as that disclosed in the application of Ashworth, Ser. No. 769,566, filed May 24, 1913, Patent No. 1,233,539, July 17, 1917. This machine comprises a work support 1 and a co-operating presser foot 2 which is 75 mounted upon one end of a presser foot lever 4 fulcrumed at 5. The presser foot is actuated during the operation of the machine to first engage yieldingly with the work, is then positively moved a predetermined distance to clamp the work during the formation of a stitch, and is finally elevated and retained in this position during the feeding movement of the work, after which the cycle of operations is repeated. In order 80 to accomplish this movement of the presser foot the lower end of the presser foot lever is connected through a link 7 with an actuating lever 8 pivoted between its ends to a controlling bar 9 which is 85 locked at predetermined intervals in a head 10 through a locking device indicated generally at 11. The lower end of the actuating lever 8 is connected through a link 12 with a tension spring 13 which normally 90 tends to swing the presser foot lever in a direction to move the presser foot into engagement with the work. The upper end of the actuating lever 8 is connected to the usual operating lever 15 through a link 16 95 to cause the operation of the actuating lever from a rotary cam disk 17. At the completion of the feeding movement of the work the controlling bar 9 is free to move and the 100

spring 13 accordingly swings the actuating lever 8 about the connection with the link 16 to move the presser foot into yielding engagement with the work. The controlling bar is then locked in position and the cam disk 17 operates through the lever 15 to swing the actuating lever about the connection with the bar 9 to move the presser foot a predetermined distance and positively clamp the work. The lock 11 is controlled in the usual manner through a curved lever 20 fulcrumed at 21 and connected to the locking lever through a link 23. The lever 20 is normally maintained in position to dock the bar through a spring 25 connected with the opposite end of the lever 20 and is unlocked through an arm 26 operatively connected with a rotary cam. It is desirable that this machine be adapted for forming a groove in the outsole whenever desired without effecting the normal operation of the presser foot. In the present invention the grooving knife is conveniently secured upon the presser foot and in order to cause the formation of a groove the presser foot actuating mechanism is arranged to maintain the presser foot in yielding engagement with the work during the feeding movement. This is conveniently accomplished by providing a lost motion connection under the control of the operator between the presser foot lever and the actuating mechanism arranged to permit the usual operation of the actuating mechanism without lifting the presser foot from the work. To this end, as shown clearly in Figs. 2 to 7, inclusive, a stud 30 is secured in the lower end of the presser foot lever 4 and is loosely received in a slot 31 formed in the link 7. The extent of movement of the stud 30 relative to the link 7 is determined by an adjusting member 32 journaled in the link at right angles to the stud 30 and having a peripheral groove 33 of varying depth formed therein opposite the stud 30. With this construction, by adjusting the position of the member 32 the clearance between the face of the member and the stud 30 may be varied as desired to vary the extent of movement of the stud 30 relative to the link 7, as shown clearly in Figs. 6 and 7. The adjusting member is provided with a slotted head 35 the periphery of which is cut away to provide oppositely disposed shoulders 36 and 37 arranged to contact with a stud 38 secured in the link 7 to determine the limit of movement of the adjusting member in opposite directions. With the adjusting member positioned as shown in Figs. 2, 4 and 6, a limited movement of the presser foot lever with respect to the link 7 may be secured, whereas with the adjusting member in the position shown in Figs. 3 and 5, the link is connected directly to the presser foot lever with no pro-

vision for a lost motion of the lever relative to the link. When it is desired to cause the operation of the presser foot in the usual manner the adjusting member is positioned as shown in Figs. 3 and 5 and the presser foot is accordingly elevated clear of the work during the feeding movement, but when it is desired to groove the outsole the adjusting member is positioned as shown in Figs. 2, 4 and 6 and upon moving the link through the actuating lever 15 to raise the presser foot the lost motion between the stud and link permits the presser foot to remain in contact with the work. During this movement the engagement of the presser foot with the work is secured by a spring 40 which connects the stud 30 with the controlling bar 9, as shown clearly in Fig. 1. In the illustrated embodiment of the invention, the grooving tool is indicated at 41 and is secured to the presser foot with the operating face of the tool projecting below the face of the presser foot by a headed fastening indicated at 42.

While it is preferred to employ the specific construction and arrangement of parts shown and described, it will be understood that this construction and arrangement is not essential except so far as specified in the claims, and may be changed or modified without departing from the broader features of the invention.

The invention having been described, what is claimed is:

1. A sewing machine comprising a presser foot, a grooving knife supported upon the presser foot, actuating mechanism for removing the presser foot from the work during the feeding operation, and means for adjusting the actuating mechanism to maintain the presser foot in yielding engagement with the work during the feeding operation.

2. A sewing machine comprising a presser foot, a grooving knife supported upon the presser foot, a presser foot lever, presser foot actuating mechanism including a link, connections between the presser foot lever and link having provision for a movement of the lever relative to the link, and means for varying the amount of relative movement of the lever and link.

3. A sewing machine comprising a presser foot, a grooving knife supported thereon, a presser foot lever, a stud secured in the lever, presser foot actuating mechanism including a link having a slot in which the stud is loosely received, and a rotatable adjusting member supported in the link and arranged to vary the extent of movement of the stud relative to the link.

4. A sewing machine comprising a presser foot lever, actuating mechanism for the lever including a link, connections between the lever and link having provision for a relative

movement of the lever and link, a rotatable adjusting member for determining the extent of the relative movement, and means for limiting the movement of the adjusting member in opposite directions.

5. A sewing machine comprising a presser foot lever, actuating mechanism for the lever including a slotted link, a stud secured in the lever and received loosely in the slot, 10 a rotatable adjusting member journaled in the link and having a peripheral groove of varying depth formed therein in operative relation to the stud, and means for determining the position of the adjusting 15 member.

6. A sewing machine comprising a presser foot, means for yieldingly pressing said foot against the work, mechanism for lifting the presser foot from the work during each 20 cycle of operations of the machine and for depressing the presser foot a predetermined distance from the position it assumes under the action of said yielding means, and means

for rendering said mechanism inoperative to lift the presser foot. 25

7. A sewing machine comprising a presser foot, a spring for yieldingly pressing said foot against the work, mechanism for raising the presser foot from the work during each work feeding interval of the cycle of operations of the machine, means for rendering said mechanism inoperative to raise the presser foot, and a second spring for holding the presser foot against the work during the work feeding interval when said mechanism is inoperative. 30 35

8. A sewing machine comprising a presser foot, means for yieldingly pressing said foot against the work, means for locking the presser foot against the work, 40 mechanism for raising the presser foot from the work during each work feeding interval of the cycle of operations of the machine, and means for rendering said mechanism inoperative to raise the presser foot.

FRED ASHWORTH.
